UNITED STATES PATENT OFFICE.

VICTOR RUBIN, OF WINNIPEG, MANITOBA, CANADA.

HOT-AIR FURNACE.

1,300,880.

Specification of Letters Patent. Patented Apr. 15, 1919.

Application filed January 11, 1918. Serial No. 211,436.

To all whom it may concern:

Be it known that I, VICTOR RUBIN, a citizen of the Dominion of Canada, residing at Winnipeg, in the county of Winnipeg and Province of Manitoba, have invented certain new and useful Improvements in Hot-Air Furnaces, of which the following is a specification.

This invention relates to improvements in hot air furnaces, and the objects of the invention are to provide a heat retaining means through which the air is circulated so that the hot air issuing from the furnace is of a high and uniform temperature; to so control the furnace gases and products of combustion that they may be circulated around the heat retaining means depending on whether a high or low temperature is desired; to adequately control the supply 10 of air delivered to the furnace; to simplify the several parts and to render the same readily accessible for inspection and generally to adapt the several parts to better 15 perform the functions required of them.

With these and other objects in view, the invention consists essentially of the improved construction particularly described and set forth in the following specification and accompanying drawings forming part 20 of the same.

In the drawings,

Figure 1 shows the furnace located in a portion of a building, partly in section and broken away.

Fig. 2 is a vertical section of the furnace.

Fig. 3 is a transverse section looking down on the line 2-2 of Fig. 2.

Fig. 4 is a transverse section looking upwardly on the line 3-3 of Fig. 2.

Fig. 5 is a transverse section looking down on the line 4-4 of Fig. 2.

Fig. 6 is a transverse section looking upwardly on the line 5-5 of Fig. 2.

Fig. 7 is a sectional elevation of a modification of the invention.

Fig. 8 is a transverse section on the line 6-6 of Fig. 7.

Fig. 9 is a transverse section on the line 8-8 of Fig. 7.

Like characters of reference refer to like parts in the several figures.

Referring to the drawings, the furnace includes a fire box 10, the wall 11 of which may be formed of metal or the like and lined 55 with fire brick 12, the said fire box being provided with a grate 13, located above the

ash pit 14, access to which is gained through the doorway 15.

A fire door 16 is also provided through which fuel may be fed to the fire box, which 60 is covered by an upper wall 17 at the rear of which a flue 18 is located.

This upper wall 17 is provided with a concentric orifice 19 above which a damper 20 operates, the said damper being located in 65 the perforated air chamber 21 concentrically located in the chamber 22, which is designed to be filled with broken glass, stones or like heat retaining means.

Air is delivered to the chamber 21 through 70 the conduit 9 extending through the side wall of the furnace and closed by a damper 8, while the damper 20 is operated externally of the furnace by the rod 7.

The chamber 22 is surrounded by a flue 75 23 divided into lower and upper compartments 24 and 25 communicating through the openings 26 and 27 located diametrically opposite each other, the opening 26 being closed by a hinged damper 28, capable of 80 being operated from the exterior of the furnace by the spindle 29 which forms a hinge pin.

The flue 23 is closed at the upper end by the wall 30 and access to the upper and 85 lower compartments 24 and 25 is gained through the doors 31 and 32 located at the front of the furnace.

The compartment 25 is connected to the smoke pipe 37 provided with a sliding damper 38 adapted to control the draft and so govern the combustion of the fuel in the fire box 10.

The furnace is inclosed by a casing 33 spaced from the wall 11 of the furnace, providing a passageway 34 through which air is passed from the inlet pipes 35. Above 95 one of these inlet pipes, a water pan 36 is located so that the air in its passage through the said jacket will take up the desired 100 amount of moisture.

The casing 33 is provided on the upper end with a transversely extending wall 39 provided with a pair of discharge conduits 40 which permit of the air heated in the furnace being distributed to the several parts of the building in the manner at present practised in heating houses by hot air.

Each of the inlet pipes 35 communicates with a duct 41 in the wall of a building so 110 that air will pass through the gratings 42 from the atmosphere, thus insuring a sup-

ply of pure air being delivered to the furnace for heating and ventilating purposes.

In that form of the invention illustrated in Figs. 7 to 9, the furnace B is provided with a fire box 10, the wall 11 of which is formed of metal or the like and is surrounded by an outer wall 45 forming an angular compartment in which broken glass, stones or other like heat retaining means are packed. Access to the fire box is gained through the door 16 and above the fire box a chamber 22^a is located surrounded by a flue 23^a which communicates with the fire box 10 in the lower wall of the chamber 22^a.

15 A circular valve 46 is employed and is designed to coact with the ports 47 formed in the bottom of the chamber 22^a. The valve 46 is provided with a spindle 48 carrying a crank arm 49 which is actuated 20 through the rod 50 extending through the lateral wall of the furnace thereby permitting the valve to be actuated externally.

By reference to Fig. 8 it will be seen that the flue 23^a communicates by means of passage 51 with passages 52 and 53 in diametrically opposite sides of the flue 23^a, said passages 52 and 53 communicating with the flue 54, so that as the products of combustion pass from the fire box into the flue 23^a 30 they are discharged through the passage 51 into the flues 52 and 53 and travel around the same and are delivered to the flue 54.

The opening 52 may be closed by a valve 55 which is vertically disposed and hinged 35 to the wall of the flue 23^a, the said hinge being provided with a crank arm 56 connected to the rod 57 which permits of the ready actuation of the valve.

40 31 is a cleaning-out door, whereby soot, ashes, or the like may be conveniently removed from the flue 54 which is in communication with the said pipe.

The furnace B is provided with an outer casing 33^a which provides a passageway between the fire box and the casing, so that air entering the said passageway through the inlet 58 can readily pass up and through the furnace B and be heated.

In other respects this furnace is similar to 50 that already described and need not be further enlarged upon.

The assembly of the several parts will be readily understood from the foregoing description.

55 The outer casing may be made in sections, as shown in Fig. 1, or formed of one piece of masonry, as shown in Fig. 2.

When the furnace is in use and a fire is lighted in the fire box 10, the products of combustion pass upwardly through the flue 18 into the compartment 24 of the flue 23 and after circulating around the chamber 22 transmit heat to the glass or broken stone filling therein and the said products of combustion then pass through the opening 27

into the upper compartment 25 and after circulating around the chamber 22 pass through the smoke pipe 37 to the chimney.

Should it be desired, however, to moderate the heat, the damper 28 may be opened 70 so that the products of combustion from the fire, after passing through the flue 18 will only come in contact with the back of the chamber 22 and instead of circulating around the same will pass directly through 75 the opening 26 into the smoke pipe 37 and thence to the chimney.

The air entering through the pipe 35 passes through the jacket 34 and circulating around the wall 11 of the furnace is thus 80 heated, and after the air has passed to the top of the furnace, it intermingles with the air passing through the inlet conduit 9, the perforated chamber 21 and chamber 22, in which the air is highly heated. 85

It will thus be seen that the air from the passageway 34 and the air passing through the heat retaining medium will on intermixing be at an even high temperature, so that the air as delivered to the conduits 40^a will 90 adequately heat the house in which the furnace is installed.

Should at any time the air chamber 21 become clogged with fine disintegrating particles entering the same through the perforations therein, this may be cleaned by opening the damper 20 by the spindle 7 and so permit the said accumulated dust falling through the orifice 19 into the fire box. 95

When that form of the invention illustrated in Figs. 7 to 9 is in operation, the fire is stoked through the door 16 and the products of combustion rise upwardly and pass into the flue 23^a where they pass around the chamber 22^a and so heat the broken glass, 105 stone or other heat retaining means located therein.

These products of combustion are discharged through the opening 51 into the flue 54 whence they pass to the rear of the 110 furnace and are delivered to the smoke pipe 37^a.

The air in the upper part of the furnace B may be permitted to pass through the chamber 22^a by actuating the valve 46 and 115 this heated air after leaving the said compartment intermixes with the air passing through the passageway 34 between the casing 33^a and the body of the furnace, the heated air being delivered through the outlet conduits 40^a to the several ventilating ducts in the house. 120

Should it be found desirable to check the heat in any way, the rod 57 is actuated so that the valve 55 is closed and the products of combustion then pass upwardly and directly into the smoke pipe 37^a. 125

By providing a heat retaining medium surrounding the body of the furnace, it will be seen that the air in its passage through 130

the inlet 58 and through the passageway 34^a will be heated to a high even temperature so that a very great heat can be obtained with a furnace of this description.

- 5 As many changes could be made in the above description and many apparently widely different embodiments of my invention within the scope of the claims constructed without departing from the spirit 10 or scope thereof, it is intended that all matter contained in the accompanying specification and drawings shall be interpreted as illustrative and not in a limited sense.

What I claim as new, is,—

- 15 1. A hot air furnace including a fire box, a compartment located above the fire box and adapted to be packed with heat retaining means and having a perforated air chamber with externally actuated valve, 20 means for passing air through the compartment and means for circulating the products of combustion from the furnace around the compartment.
- 25 2. A hot air furnace including a fire box, a compartment located above the fire box and designed to be filled with heat retaining means and having a perforated air chamber with externally actuated valve, means for passing the products of combustion around 30 the compartment, and a smoke pipe and valve means designed to control the passage of the products of combustion and deliver the same directly to the smoke pipe when it is desired to check the heat.
- 35 3. A hot air furnace including a fire box, a compartment located above the fire box and designed to be filled with heat retaining means and having a perforated air chamber,

a valve in the compartment through which air is designed to pass and means for actuating the valve. 40

4. A hot air furnace including a fire box, a compartment located above the fire box and designed to be filled with heat retaining means and having a perforated air chamber, 45 a flue around the compartment, means for delivering the products of combustion to the flue, a valve in the flue controlling the direction of flow of the products of combustion and an air passageway, as and for the purpose specified. 50

5. A hot air furnace including a fire box, a compartment located above the fire box and designed to be filled with heat retaining means and having a perforated air chamber, 55 a pair of flues surrounding the said compartment, means for circulating the products of combustion successively through each flue and means for passing air through the said compartment. 60

6. A hot air furnace including a fire box, a compartment located above the fire box and designed to be filled with heat retaining means, a pair of flues concentrically located around the said compartment, valve means 65 in one of the flues designed to permit the products of combustion to pass successively from one flue to the other and means for passing air through the compartment.

In testimony whereof I affix my signature 70 in the presence of two witnesses.

VICTOR RUBIN.
